UNITED STATES PATENT OFFICE.

ERNEST J. SPANG, OF CHICAGO, ILLINOIS.

PENCIL ATTACHMENT FOR FOUNTAIN PENS.

Application filed November 2, 1923. Serial No. 672,359.

To all whom it may concern:

Be it known that I, ERNEST J. SPANG, a citizen of the United States, residing at Chicago, in the county of Cook and State of Illinois, have invented new and useful Improvements in Pencil Attachments for Fountain Pens, of which the following is a specification.

This invention relates to a combination 10 pen and pencil and more particularly to a pencil attachment for fountain pens as set forth in my copending application for patent filed August 30, 1923, Serial No. 660,185.

The primary object of this invention is to 15 provide a unitary structure which may be readily attached to the barrel of a fountain pen and will properly feed the lead when operated in a very simple manner.

An object of the invention is the combination 20 and arrangement of parts whereby the cost of manufacture will be greatly reduced.

A feature of my invention is the novel 25 manner of connecting parts so that they may be readily disconnected.

With these and other objects in view the invention will be better understood from the following detailed description taken in connection with the accompanying drawing 30 wherein:

Fig. 1 is a side elevation of a pen structure showing the pencil attachment at one end thereof.

Fig. 2 is an enlarged sectional view of my 35 improved attachment.

Fig. 3 is a sectional view on the line 3—3 of Fig. 2.

Fig. 4 is a side elevation of the tube and its associate parts.

Again referring to the drawing illustrating 40 one of the many constructions of my invention the numeral 1 designates a pen structure which may be of any of the well known designs having one end portion 2

open so that my improved pencil structure 45 may be quickly and readily attached thereto. My improved pencil structure consists of a sleeve 3 removably fitted in the open end 2 but frictionally held against rotation.

Rotatably mounted in the sleeve 3 is the plug 4 having a ring portion 5 exposed so as to 50 be engaged by the fingers of the user for turning the plug within the sleeve. This plug also includes an annular flange 6 to 55 which is frictionally attached the shell 7 which has a lead opening 8. My improved

lead projecting means 9 consists of a tube 10 secured to the plug 4 and provided with a longitudinally extending slot 11. The inner end of the sleeve 3 is provided with an inwardly extending annular guide flange as illustrated in Fig. 2. The tube 10 has an enlarged upper end which frictionally engages the inner wall of the barrel 4' on the plug 4. This barrel 4' extends inwardly 65 from the plug opposite the flange 6 and is rotatably mounted within the sleeve 3 as shown in Fig. 2. A spiral member 12 is provided which may be in the form of a coil spring having one end attached to the collar 70 13 as indicated at 14. This collar 13 in turn is attached to the sleeve 3 by the screw 15. The inner end of the barrel 4' is provided with an inturned annular flange which is adapted to rotatably engage the collar 13 75 75 as indicated at 16. This collar 13 in turn is attached to the sleeve 3 by the screw 15. The inner end of the barrel 4' is provided with an inturned annular flange which is adapted to rotatably engage the collar 13 75 whereby the barrel 4' and the tube 10 will rotate independent of the sleeve 3 upon the turning movement of the ring 5. It will be noted that the collar 13 has a reduced portion which engages the inner perimeter 80 of the flange on the inner end of the sleeve 3 and receives the screw 15 which connects the collar 13 to the sleeve 3. A ring 16 is interposed between the collar 13 and adjacent the end of the split tube. A follower 85 17 operates within the spiral member against the end of the lead and has a lug 18 moving between the convolutions of the spiral member and in the slot 11, and thus it will be seen that by turning the ring 5 thereby 90 plug 4 and tube 9 will be turned for moving the follower along the spiral member and thereby force lead through the lead opening 8. It will be noted the parts may be quickly 95 attached to the end of the barrel of a pen structure and the various parts may be disconnected from each other. It will also be noted the parts may be assembled so as to reduce the cost of manufacture.

It is, of course, to be understood that the exact shape and manner of connecting the parts may be changed at will without departing from the spirit of this invention, therefore, I do not desire to be limited in any manner except as set forth in the claims 105 hereunto appended.

Having thus described my invention what I claim is:

1. In combination with a fountain pen structure having one end open, a sleeve fitted in said open end, a rotatable plug, a barrel formed on the plug and disposed within

- the sleeve for rotative movement independent of the sleeve, a shell removably supported by said plug, a tube in the shell, an enlarged portion at the inner end of the tube frictionally engaging the inner wall of the barrel for rotation therewith, and means carried by the tube for feeding a lead therethrough upon rotation of the plug.
2. In combination with a fountain pen structure having one end open, a sleeve fitted in said open end, a barrel integral with the plug and rotatably mounted in said sleeve, an annular flange on the plug extending in a direction opposite the barrel, a tapering shell having its larger end removably engaged with the flange, a tube within the shell having one end extending in the barrel, an enlarged portion on the inner end of the tube having engagement with the interior of the barrel for simultaneous rotation, a longitudinal slot in said tube, a lead follower in the tube, a lug on the follower engaging in the slot, and means supported from the inner
- 5
- 10
- 15
- 20

end of the sleeve whereby to move said follower through the tube upon the rotation 25 of the plug.

3. In combination with a fountain pen structure having one end open, a sleeve fitted in said open end, an internal annular flange on the inner end of the sleeve, a plug 30 at the end of the open structure, a barrel on the plug rotatably mounted in the sleeve, an annular flange on the plug extending in a direction opposite the barrel, a tapering shell having its large end removably mounted upon the flange, a tube within the shell, an enlarged portion on one end of the tube having engagement with the interior of the barrel for rotation therewith, a lead feeding means supported from the internal flange 35 on the sleeve and actuated through the rotation of the plug for feeding lead through the tube.

In testimony whereof I affix my signature:

ERNEST J. SPANG.
